Specification for Design.

Patented Aug. 2, 1921.

Application filed July 13, 1920. Serial No. 396,021. Term of patent 14 years.

To all whom it may concern:

Be it known that I, ENDRE BALOGH, a citizen of Hungary, residing at Newark, in the county of Essex and State of New Jersey, have invented a new, original, and ornamental Design for an Envelop, of which the following is a specification, reference being had to the accompanying drawing, forming part thereof.

folded blank from which the envelop is formed.

Fig. 2 is a plan view of the envelop shown partially folded.

Fig. 3 is a plan view of the same completely folded.

I claim:—

The ornamental design for an envelop as shown.

ENDRE BALOGH.
